BOTH OF BOULDER, COLORADO.

FLUID-FEED SIDE-INLET DRILL-BIT.

No. 845,385.

Specification of Letters Patent.

Patented Feb. 26, 1907.

Application filed October 5, 1906. Serial No. 337,614.

To all whom it may concern:

Be it known that I, JOHN HENRY Wiest, residing at Boulder, in the county of Boulder and State of Colorado, have invented a new and Improved Fluid-Feed Side-Inlet Drill-Bit, of which the following is a specification.

This invention relates to improvements in that type of hollow rock-cutting drill-bits having side inlets; and it comprehends generally a new and useful means for detachably connecting the fluid-conveying pipe to the side inlet of the drill-bit in such manner that when water is used it cannot come in contact with any of the working parts of the machine and whereby the fluid-supply can be located at any place desired and fed to the drill under atmosphere or forced pressure.

In its more specific nature my invention embodies an improved construction of coupling or holding device for removably coupling or holding the discharge end of the fluid-pipe in tight connection within the side inlet of the drill, capable of such adjustment whereby the fluid-pipe can be expeditiously and conveniently applied or removed and held to suit the desired positioning of the drive-bit; and it also consists in further subordinate features and details of construction, all of which will be hereinafter fully described, pointed out in the appended claims, and illustrated in the accompanying drawings, in which—

Figure 1 is a perspective view of a side-inlet drill-bit with my improvements applied. Fig. 2 is a central transverse section thereof. Fig. 3 is a longitudinal section taken on the line 3 3 on Fig. 2. Fig. 4 is a perspective view of the coupling with the fluid-feed pipe attached, the coupling being shown in its closed or coupled position. Fig. 5 is a perspective view, the coupling being in its uncoupled position and the nozzle member 1 omitted. Fig. 6 is a transverse section, similar to Fig. 2, of a slightly modified for a hereinafter referred to.

In carrying out my invention I provide a nozzle piece or member 1, adapted to be quickly fitted within the side inlet 20 of the drill-bit 2, which latter may be of any improved form, but of that type having its central bore or fluid-channel stopped at the inner or striking end of the bit and connected with a side inlet 20, as clearly shown in Fig.

3, and the rock-cutting end may also be of the usual type, as shown.

In the adaptation of my invention to side-inlet drill-bits the side inlet need not be threaded and is preferably smooth to receive the tapered end 10 of the nozzle 1, which at the base of the taper 10 is externally threaded, as at 11, to adjustably receive the base or main coupling member 3, and the threaded end of the nozzle is suitably shaped to conveniently receive and hold the flexible hose or tubing 4, that leads to the tank or other point of supply which may be led to the drill under natural or fluid pressure, as desired.

The member 3 has a pendent apertured lug 30 at one end, and its opposite end is formed with a bifurcated extension in the nature of apertured ears 31, the outer and upper edges of which are curved, as at 32, and terminate in a slightly concaved or depressed edge portion 33, the reason for which will presently appear, and between the said ears 31 is fulcrumed the coupling-lever 5, pivoted on the cross-pin 50 and having a concaved bearing 51 on its under edge adjacent the fulcrum and suitably-shaped handle extension, as shown.

6 designates an L-shaped coupling member, one end 60 of which is bifurcated, the ears 61 being apertured and arranged to pivotally connect with the pendent lug 30 on part 3, while the other end is flattened to form an ear 62, which is also apertured to receive a pivot-pin 7, that joins the apertured ends 80^a of a locking yoke or member 8, whose cross-bar 81 cooperates with the curved edges 33 of the member 3 and the locking-lever.

From the foregoing, taken in connection with the accompanying drawings, the advantages and the method of operating my improvement, it is believed, will be readily apparent.

By reason of fitting the feed-tube to the coupling in the manner shown and described it will be apparent that when the coupling is operated, as shown in Fig. 2, to join my fluid-feed with the side inlet of the drill it is only necessary to slip the tapered nozzle into the side inlet of the drill, a close joint being effected by reason of the member 3 being held flatwise against the inlet side of the drill, to which position the member 3 is locked by

simply swinging the yoke member 8 over the curved edges of the member 3 and then bringing down the lever 5, which tightly clamps the several parts about the drill-stock 5 and causes the cross-bar to firmly seat in the depression 33, as best shown in Fig. 2.

By reason of the manner in which I am enabled to connect the fluid or feed pipe to the drill-stock the same can be almost instantly 10 applied or disconnected, since no nuts, bolts, or unscrewing of the parts is necessary to adjust the same for the drill-stock.

In Fig. 6 I have illustrated a nipple as provided with a rubber gasket 10^a, which is detachably fitted on the end and is adapted to be quickly replaced when it becomes worn or damaged. By providing the nipple with a rubber gasket, as shown, a twofold purpose is accomplished, since the said gasket stops 20 any leak that might be caused by the nipple becoming worn, and, secondly, the said gasket acts as a spring and serves to take up the wear and keeps the clamp tight at all times.

Having thus described my invention, what 25 I claim, and desire to secure by Letters Patent, is—

1. In combination with a rock-cutting drill-bit, having a fluid-passage extended into it from the drilling end and having a smooth 30 side inlet to said passage; of a fluid-feed member which includes a smooth discharge-nipple end, and clamping means mounted on the nipple end for engaging the drill-stock and coupling said nipple in the inlet as set forth.

2. As an improvement in side-feed rock-drills, the combination with a hollow drill-bit having a side-feed inlet; of a feed-pipe having a nozzle adapted to enter the bit side- 40 feed inlet, a member mounted on the nozzle adapted to clamp against one side of the bit-stock and a yoke-frame pivotally mounted on the said member, said yoke-frame including a locking portion adapted to interlock

with the member on the nozzle and a lever 45 device on the said member for moving the yoke into a locked engagement with the drill-stock as set forth.

3. The combination with the drill-stock having a longitudinal fluid-passage that terminates in a lateral or side-feed inlet; of a flexible fluid-pipe, a metallic discharge-nipple connected to the pipe, a clamp member 50 adjustably mounted on the nipple whose upper end has a bifurcated extension, whose 55 outer edges curved, an L-shaped clamp pivotally mounted on the lower end of the adjustable clamp member, a yoke pivotally connected to the outer end of the L-shaped clamp, said yoke being adapted to swing over 60 and engage the curved edge of the adjustable clamp members and a lever fulcrumed on the upper end of the clamp member for engaging the cross members of the yoke as set forth.

4. As a new article, a clamp for the purpose described, comprising a main member, a nipple detachably and pivotally mounted thereon, said member having a bifurcated extension at the upper end, and an apertured pendent ear at the lever end, an L-shaped 65 clamp member hinged at one end to the pendent ear of the main member, a yoke-frame pivotally connected to the outer end of the L-shaped member, a yoke-frame pivotally connected to the said other end of the L-shaped member, said yoke being adapted to swing down over the bifurcated extension of the main member and a lever pivotally mounted in the said bifurcated extension 70 adapted to engage the yoke-frame and hold 75 it in a locked engagement with the plate having the bifurcated ears and pendent lug as set forth.

JOHN HENRY Wiest.
